(73) Assignee: **F3M3 Companies, Inc.**, Miramar, FL (US)

(57) **CLAIM**
The ornamental design for a removable shoe tongue for transmitting electronic data to a game, as shown and described.

(**) Term: **14 Years**

DESCRIPTION

(21) Appl. No.: **29/397,150**

FIG. 1 is a front perspective view of the removable shoe tongue for transmitting electronic data to a game.

(22) Filed: **Jul. 12, 2011**

FIG. 2 is a rear perspective view of the removable shoe tongue for transmitting electronic data to a game.

(51) LOC (9) Cl. **02-99**

FIG. 3 is a front elevation view of the removable shoe tongue for transmitting electronic data to a game.

(52) U.S. Cl. **D2/975; D2/946; D14/432**

FIG. 4 is a top view of the removable shoe tongue for transmitting electronic data to a game in use.

(58) Field of Classification Search **D2/946;**

FIG. 5 is a bottom view of the removable shoe tongue for transmitting electronic data to a game.

..... **D2/975; D14/412, 419, 432; 36/54**

FIG. 6 is a side view of the removable shoe tongue for transmitting electronic data to a game.

See application file for complete search history.

FIG. 7 is a front view of the removable shoe tongue for transmitting electronic data to a game; and,

(56) **References Cited**

FIG. 8 is a rear view of the removable shoe tongue for transmitting electronic data to a game.
